(57) **CLAIM**

The ornamental design for a notebook computer with touch screen, as shown and described.

DESCRIPTION

FIG. 1 is a top right front perspective view of a notebook computer with touchscreen in a closed configuration;

FIG. 2 is a back view thereof;

FIG. 3 is a bottom plan view thereof;

FIG. 4 is a right side view thereof, which is a mirror image of left side view thereof;

FIG. 5 is a top plan view thereof;

FIG. 6 is a front view thereof;

FIG. 7 is a top right front perspective view of a notebook computer with touchscreen in a laptop configuration (the keys have not been included for ease of illustration);

FIG. 8 is a top right back perspective view thereof (the keys have not been included for ease of illustration);

FIG. 9 is a top plan view thereof;

FIG. 10 is right side view thereof, which is a mirror image of a left side view thereof;

FIG. 11 is a top plan view of a notebook computer with touchscreen in a tablet configuration;

FIG. 12 is a right side view thereof, which is a mirror image of a left side view thereof;

FIG. 13 is a top right front perspective view thereof; and,

FIG. 14 is a back view thereof.
